SIGNORS TO THE O. M. EDWARDS COMPANY INC., OF SYRACUSE, NEW YORK, A COR-
PORATION OF NEW YORK

WEATHER-STRIP CONSTRUCTION FOR WINDOW SASHES

Application filed July 1, 1929. Serial No. 375,180.

This invention relates to window sashes and has for its object, a weather strip for the bottom rail of the sash, which weather strip is yielding or resilient and shaped to conform 5 to an inclined window sill when the sash is lowered against the sill to conform for irregularities in the sill surface.

The invention consists in the novel features and in the combinations and constructions 10 hereinafter set forth and claimed.

In describing this invention, reference is made to the accompanying drawings in which like characters designate corresponding parts in all the views.

15 Figure 1 is a fragmentary elevation of a window sash embodying this invention.

Figure 2 is an edge view of parts seen in Figure 1 and the contiguous portion of the sill, the sash being shown in its closed position with the weather strip compressed 20 against the sill.

Figure 3 is a view similar to Figure 2 showing the sash as away from the sill and the weather strip in its normal form.

25 The sash may be of any suitable form, size and construction and includes the usual stiles, rails and glass pane.

It will be understood that the sash is 30 guided during its raising and lowering movement in the window frame in any suitable manner.

1, 2 and 3 designate respectively, one of the stiles, the bottom rail and the glass pane.

35 4 designates the sill which is shaped to provide a stop at 5 at the inner surface of the bottom rail when the sash is closed and with an outwardly and usually downwardly sloping surface 6 on which the weather strip rests 40 and compresses when the sash is closed.

4^a designates the window guide or channel at each edge of the sash.

The bottom rail 2 may be of any suitable form, size and construction. It is here shown 45 as formed up of sheet metal U shape in general form with a re-entrant groove 7 in its top for receiving the glass pane 3 and the marginal packing or channel of yielding material in which the glass pane seats. The 50 channel formation is open at the lower edge

of the bottom rail and provided with in-turned flanges 8. The construction of the bottom rail forms no part of this invention.

9 designates the weather strip which extends lengthwise of the lower edge of the bottom rail. The weather strip here shown includes a base portion 10 which is enclosed in a metal casing 11, in the form of an inverted channel, the side walls of the channel having inwardly extending flanges 12 which slidably fit channels formed by bending back the in-turned flange 8 of the side walls of the bottom rail 2.

55 The weather strip is inserted in the bottom rail by an endwise sliding movement. This 60 feature forms no part of this invention.

The base 10 is formed with grooves in its side faces for receiving the in-turned flanges 8. The construction thus far described forms no 65 part of this invention.

70 The portion of the weather strip below the bottom rail is formed hollow and of a general triangular shape in cross section, the hypotenuse of the triangular formation being arc shaped providing an arc shaped outer wall 75 13 which engages the surface 6 of the sill, one of the legs of the triangle abutting against the internal flanges 8 at the lower edge of the bottom rail 2, and the other leg 14 of the triangular formation being parallel to the outer face of one of the side walls of the bottom rail and preferably flush therewith.

The internal cavity 15 of the weather strip is 80 also triangular in general form with a wall with the hypotenuse thereof substantially parallel to the outer wall 13 of the weather strip and the wall 16 along one of the legs of the triangular formation opposed to the plane of the lower edge of the bottom rail parallel to the third wall 17 of the triangular formation extending in the same direction as the outer wall 14 of the weather strip but normally inclined out of a plane parallel to the wall 14, the inclination being upwardly away from such wall 13, so that the upright wall 14 is thicker at its top and bottom.

85 The upright wall 14 is thicker and more rigid than the hypotenuse wall 13.

90 Owing to the shape of the lower portion 8 of the weather strip and the formation of the 100

internal cavity 15, the wall at the hypotenuse of the triangular formation readily conforms to the surface 5 of the sill and to any irregularities therein due to any particles of dirt etc., adhering thereto so that the sash is weather tight along the bottom rail, when closed and also owing to the wall 14 and its formation, it yields slightly outwardly, (Figure 2) when the wall 13 is compressed, so that the nose at the angle of the two walls is forced outwardly against the guide strip 4^a when the sash is closed and prevents the accumulation of dust that would otherwise occur in the pockets at the ends of the weather strip in the guides 4^a whereby dust works under the weather strip under the force of the wind created by the train in motion.

What we claim is:

20 1. A window sash having a weather strip along the edge of its bottom rail for coacting with the sill of the window frame, said weather strip being formed of resilient material and formed hollow and having its lower sill engaging surface inclined and one of its outer surfaces vertical and located in the plane of one side face of the bottom rail.

30 2. A window sash having a weather strip along the edge of its bottom rail for coacting with the sill of the window frame, said weather strip being formed of resilient material and formed hollow and having its lower sill engaging surface inclined and one of its outer surfaces vertical and located in the plane of one side face of the bottom rail, the wall on which said lower surface is formed being flexible and the wall on which said upright surface is provided being arranged to receive compression force when the sash is against the sill.

40 3. A window sash having a weather strip along the edge of its bottom rail for coacting with the sill of the window frame, said weather strip being formed of resilient material and formed hollow and having its lower sill engaging surface inclined and one of its outer surfaces vertical and the internal cavity of the weather strip being normally of general triangular form with the wall thereof at the hypotenuse of the triangular formation substantially parallel to the sill engaging surface of the weather strip.

50 4. A window sash having a weather strip along the edge of its bottom rail for coacting with the sill of the window frame, said weather strip being formed of resilient material and having a triangular portion formed hollow and having its lower sill engaging wall inclined and one of its outer walls upright.

60 5. A window sash having a weather strip along the edge of its bottom rail for coacting with the sill of the window frame, said weather strip being formed of resilient material, the portion of the weather strip below the bottom rail being hollow and tri-

angular in general form with the hypotenuse of the triangular formation normally arc shaped and one of the legs of the triangular formation abutting against the edge of the bottom rail and the other leg located in the 70 plane of one of the side faces of the bottom rail to present a continuous surface flush with said side face of the bottom rail.

6. A window sash having a weather strip along the edge of its bottom rail for coacting 75 with the sill of the window frame, said weather strip being formed of resilient material, the portion of the weather strip below the bottom rail being hollow and triangular in general form with the hypotenuse 80 of the triangular formation normally arc shaped and one of the legs of the triangular formation being horizontal and abutting against the edge of the bottom rail and the other leg being upright and located substantially in the plane of one of the side faces of the bottom rail, the internal cavity of the weather strip being located in the triangular portion of the weather strip and being also triangular in general form with the hypotenuse 85 of the triangular formation substantially parallel to the outer curved face of the weather strip.

7. A window sash having a weather strip along the edge of its bottom rail for coacting 95 with the sill of the window frame, said weather strip being formed of resilient material, the portion of the weather strip below the bottom rail being hollow and triangular in general form with the hypotenuse 100 of the triangular formation normally arc shaped and one of the legs of the triangular formation being horizontal and abutting against the edge of the bottom rail and the other leg being upright and located substantially in the plane of one of the side faces of the bottom wall, the internal cavity 105 of the weather strip being located in the triangular portion of the weather strip and being also triangular in general form with the hypotenuse 110 of the triangular formation substantially parallel to the outer curved face of the weather strip, the upright wall of the triangular formation being thicker than the 115 hypotenuse wall.

8. A window sash having a weather strip along the edge of its bottom rail for coacting with the sill of the window frame, said weather strip being formed of resilient material, the portion of the weather strip below the bottom rail being hollow and triangular in general form with the hypotenuse 120 of the triangular formation normally arc shaped and one of the legs of the triangular formation being horizontal and abutting against the edge of the bottom rail and the other leg being upright and located substantially in the plane of one of the side faces of the bottom wall, the triangular portion 125 of the weather strip and being also triangu- 130

lar in general form with the hypotenuse of the triangular formation substantially parallel to the outer curved face of the weather strip, the upright wall of the triangular formation being thicker than the hypotenuse wall and thicker at its top than at its bottom.

5 9. A window sash having a weather strip along the edge of its bottom rail for coacting with the sill of the window frame, said weather strip being formed of resilient material and being of hollow formation, a lower sill engaging wall located below said hollow portion, and an upright wall located in front of said hollow portion and of heavier cross section than the sill engaging wall for carrying the weight of the sash with little flexing of the upright wall.

10 15 In testimony whereof, we have hereunto signed our names, at Syracuse, in the county of Onondaga and State of New York, this

20 22nd day of June, 1929.
